MOP CLAMP

Simon Brandel, Conshohocken, Pa.

Application October 17, 1934, Serial No. 748,739

1 Claim. (Cl. 306—1)

This invention relates to novel clamp structures of a generically similar type expressly constructed and designed for use in connection with a handle such as is attachable to a special brush, 5 mop head or the like.

Briefly described, the preferred embodiment of the invention comprises a clamp structure made up principally of a duplex or double jaw clamp wherein the jaws are fashioned to engage and hold in place a brush, mop head or the like, together with a retaining bracket of an adapter type such as enables it to accommodate and cooperate with the movable jaw of the clamp arrangement according to the selection and discretion of the user.

In reducing the invention to practice I have evolved and produced a simple and economical clamp construction having a socket for reception of the stick or handle so as to permit said 20 socket to function as a ferrule and as a carrier for the companion or complementary clamping units.

The specific adaptation and arrangement of parts will become more readily apparent from 25 the following description and drawings.

In the drawings:

Figure 1 is an elevational view of one embodiment of the invention showing the arrangement utilized for the accommodation of a stiff back 30 bristle brush.

Figure 2 is a view like Figure 1 showing the alternative arrangement such as is utilized for holding a mop head such as, for example, of the 35 type used in connection with ordinary floor and wall mops.

Figure 3 is an elevational view of Figure 1 observing the same in a direction from right to left.

Figure 4 is a view in section and elevation disclosing the assemblage a little more in detail.

Figure 5 is an elevational view of the relatively movable or swingable unit of the clamping jaw construction.

Figure 6 is a perspective view of the special adapter used in connection with the arrangement 45 illustrated in Figure 1.

Figure 7 is a view of a similar bracket or adapter used in connection with the arrangement depicted in Figure 2.

By way of introduction, it is to be pointed out 50 that the clamping device itself is the same in both embodiments of the invention. The only difference is predicated on the specific formation or shape of the adapter bracket illustrated in Figures 6 and 7. That is to say, the one shown 55 in Figure 6 is of the right angular or acute angle

type allowing the jaws to be spread sufficiently to accommodate the back of a brush. The one shown in Figure 7 is of the obtuse angular formation and is used in Figure 2 where it is necessary to bring the clamping jaws into close grasping relationship to the relatively small portion of the mop head. It follows, therefore, that the numerals throughout the drawings are utilized to designate like parts with the exception of the details shown in Figures 6 and 7. That is to say, these parts will be differentiated by distinguishing numerals merely for the sake of illustration and clearness. 5

As before briefly indicated, the clamping device is composed principally of two complementary 15 sections or parts, one of which is designated as the stationary section and denoted by the numeral 8 and the other one distinguished by the numeral 9. The part 8 comprises a socket 10 shaped to accommodate the stick or handle 11 20 and therefore functions as a ferrule. Formed integrally on the lower end of the socket is the complementary jaw unit and this embodies as better shown in Figure 4 a flattened shank 12 fashioned and shaped as disclosed to form what 25 may be conveniently designated as a hanger lug. The jaw element, which is channel-shaped in cross sectional contour, is distinguished by the numeral 13 and the walls thereof are serrated as at 14 to provide gripping teeth. The jointing 30 connection between the parts 12 and 13 is shown in Figure 3 and comprises a longitudinally bowed or arched connector 15 and a centralized brace element 16 connected therewith and with the corresponding central portion of the channeled 35 jaw 13.

The section 9, which constitutes the swingable jaw unit, is of somewhat similar construction. Referring to Figure 5, for example, it will be observed that this embodies a channel-shaped 40 clamping jaw 17 having gripping teeth 18. In this arrangement it will be observed, however, that the connector bar 19 is of longitudinally bowed form and made integral with the jaw and carries a pair of upstanding attaching ears 20. 45 These ears straddle the aforementioned hanger lug 12 and are pivotally connected thereto by a pin as indicated at 21. The numerals 22 designate a pair of spaced parallel brace elements between the bar 19 and the central portion of the 50 jaw 17. This provides a sort of a framework for hinged connecting the jaw 17 with the relatively fixed jaw unit 8. Whenever the device is adapted for use in connection with a brush as indicated at 23 it is necessary to provide a right 55

angularly shaped adapter bracket 24. This functions as a retaining element. It will be observed from Figure 6 that it comprises a transversely curved attaching member 25 and a substantially right angularly bent retaining member 26 having a stabilizing detent 27 which rests upon the bar 19 and is located between the brace elements 22 to provide for rigidity of construction. It will be noted that the adjacent lower end portion on the same side of the socket 10 is formed with a cut-out portion or notch to accommodate the attaching member 25. This part 25 is held in place by a bolt 28 and a wing nut 29. The angular relationship of the features 26 and 27 allows the jaw units 8 and 9 to be spread apart sufficiently to securely grasp the brush 23. Incidentally the brush embodies a stiff back 30 and brush bristles 31. The marginal portion of the back is provided with a groove 32 to accommodate the adjacent teeth 14 and 18 as the case may be. It is evident, therefore, that the brush may be conveniently located between the jaw units and firmly secured in place against displacement.

Whenever the invention is desired for use with a soft or flexible mop head as indicated at 33 in Figure 2, the same construction already described is satisfactory for use. The only difference is that the adapter bracket 34 is changed in formation. Fundamentally, however, it is the same in that it embodies an arcuate or channel-shaped attaching member 35 apertured to accommodate the bolt 28 and further embodies a terminal member or portion 36 which serves as a pressure element to bear against the adjacent or complementary jaw unit. This part 36, however,

is disposed at a more obtuse angle to the member 35 than is the case with the features illustrated in the bracket shown in Figure 6. It is of course understood that the bracket 24 in Figure 6 is not a true right angle but is approximately so and has been so described merely for convenience. 5

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice, if desired.

What is claimed is:

A structure of the class described comprising a handle-receiving socket, an integral jaw unit carried thereby, said jaw unit including a shank 20 formed with a hanger lug, and further including a horizontally disposed longitudinally elongated channel-shaped clamping jaw, each longitudinal free edge thereof being serrated, means attaching said jaw to said hanger lug, a relatively 25 movable jaw unit hingedly attached to said lug and including a jaw corresponding in formation to the first-named jaw, a detachable adjusting and retaining bracket cooperable with said socket, said bracket being of such angular forma- 30 tion as to regulate the space or distance between the two clamping jaws so as to allow said jaws to be employed in conjunction with either a stiff back brush or a soft mop head as desired.

SIMON BRANDEL. 35
